UNITED STATES PATENT OFFICE.

JOHN LAWSON, OF CENTRAL FALLS, RHODE ISLAND, ASSIGNOR TO HEMPHILL MANUFACTURING COMPANY, A CORPORATION OF RHODE ISLAND.

THREAD-SEVERING DEVICE FOR KNITTING-MACHINES.

1,293,812.

Specification of Letters Patent. Patented Feb. 11, 1919.

Application filed January 25, 1911. Serial No. 604,550.

To all whom it may concern:

Be it known that I, JOHN LAWSON, a citizen of the United States, residing at Central Falls, in the county of Providence and State of Rhode Island, have invented certain new and useful Improvements in Thread-Severing Devices for Knitting-Machines, of which the following is a specification.

10 The present invention relates to improvements in circular automatic stocking-knitting machines, and it consists more particularly in improved means for automatically severing the knitting-thread or threads at predetermined points during the knitting of the stocking. Or, in other words, the object of the present invention is to provide 15 knitting-machines of the class referred to with a simple, inexpensive and efficient device for automatically severing one or more of the floating or temporarily inactive threads from the web while the other thread or threads are being knitted into the fabric; the device being further adapted to sever 20 all the threads connecting the web and supply at the completion of the stocking.

The thread-cutting device is or may be employed in connection with, but independently of, a self-acting binder or clamping 25 mechanism arranged to hold the free end of the threads leading from the respective bobbins or cones. In the type of knitting-machine indicated in the drawings, the said thread-clamping and severing devices are normally disposed inside the needle-row of 30 the knitting-cylinder and mounted on members fixed to the swinging latch-ring; the arrangement being such that the said devices are bodily movable with the latch-ring, the binder at the same time holding 35 the free ends of the supply-threads. It may be added that the thread-cutting device is normally located inside of the needle-row and adjacent the upper part of the web.

40 The arrangement and timing of the thread-binder and the severing device are such that when a thread is moved out of knitting action, it is at the same instant engaged and held by the binder, the cutting-device immediately thereafter severing the thread 45 from the web.

In the accompanying sheet of drawings, Figure 1 represents an end elevation of an automatic stocking-knitting machine show-

ing my present invention; portions of the mechanism being omitted. Fig. 2 is a corresponding front side elevation; the latch-ring and portions of the cylinder being shown in section. Fig. 3 is a plan view of the latch-ring, &c., corresponding with Figs. 60 1 and 2. Fig. 4 is a side elevation of the thread-cutting device proper, in enlarged scale, the cutting-jaws being open; and Fig. 5 is a similar view, showing the jaws closed.

It may be stated here that the present 65 invention is well adapted to the type of knitting-machine illustrated and described in U. S. Patent #933,443, granted to J. D. Hemphill, September 7, 1909, and to which reference may be made. That is to say, in 70 the accompanying drawings are indicated a frame or housing a , surrounded by a table, a revoluble knitting-cylinder N , with its sinker-ring n^e and cap-ring G , a swinging latch-ring C provided with an extension d^3 , 75 normally supported by a standard K , spring-pressed thread-guides d^1 , a lifting-finger f^s therefor, a cam-carrying shaft s^1 , &c. The construction and manner of operation of these elements are or may be substantially the same as set forth in the patented knitting-machine above referred to.

In the present invention or thread-cutting device, the same, except the actuating mechanism, is or may be detachably connected to the swinging latch-ring C and being bodily movable with it. The latch-ring itself is pivoted at c^2 to the rear standard c^1 , as clearly shown in Fig. 1. A bent arm or bracket c^3 is secured to the ring C contiguous to the pivot point, its free end portion extending toward the front and terminating within the ring's central space or needle-row in a substantially flat plate B , on 80 which latter is mounted a binder or thread-clamping member a^2 , capable of angular movement, the same being employed for holding the floating or temporarily inactive threads out of engagement with the needles. 85 This latter device, however, forms the subject of U. S. Patent #935,981, granted to J. D. Hemphill, October 5, 1909.

Referring now more particularly to the accompanying drawing, one edge (the left when viewed from the front of the machine) 90 of the main plate B is provided with a steel bar or blade b constituting the fixed cutting jaw member and having a lever-like blade

b^1 , pivoted at b^2 , arranged to coöperate with the member b to produce a shearing action upon the thread or yarn lying between the jaws. A horizontally disposed two-arm lever h is pivoted at h^1 to said bracket c^2 , its inner arm being jointed to a short link h^2 , in turn jointed to a bent member h^3 secured to the swinging lever-blade b^1 . The outer member of lever h is provided with an arc-shaped slot e of suitable radius, described from pivot c^2 , in which the upper end of the vertically guided, endwise movable rod e^1 is slidably jointed. By means of this construction and arrangement of the coöperating parts, it will be seen that the shearing device moves bodily with the latch-ring whenever the latter is swung on its pivot c^2 , the slotted part e meanwhile moving while the rod e^1 is or may be temporarily stationary. It may be added that the cutting-jaws are kept normally closed, as indicated in Fig. 5, and are opened only when a thread is moved out of knitting action. The act of opening and closing the jaws to quickly sever the thread occurs nearly simultaneously or concurrently with the action of rendering the corresponding thread inactive; the binder however engages the thread before it is severed. The means represented for thus opening the jaws are as follows:

To the outer left end of the main cam-shaft s^1 is fixed a disk-like wheel i having a series of short, suitably spaced lugs i^1 disposed around its periphery. It may be stated that the arrangement or positioning and timing of these lugs bear a direct relation to the points in the knitting of the stocking when the knitting-threads are to be temporarily moved out of knitting action. The cam-shaft and its members make one complete revolution during the production of the stocking; its movements being effected in an intermittent or step-by-step manner through the medium of a pattern-chain and co-acting devices (not shown) in a well-known way. A horizontal tilting-lever g , fulcrumed at a^2 , has its front or free end g^1 engageable with the periphery and lugs of said wheel i during the rotation of the cam-shaft (Fig. 1) by means of the pull-spring s^2 . To the other or rear end of lever g is jointed a vertical rod m having its upper end jointed to a short tilting-lever m^1 , fulcrumed at m^2 , in turn jointed to the lower end of the said vertically guided rod e^1 , connected with the lever h , as before stated.

My improved thread-cutting device is located inside the circular needle-row and having the shearing-blades normally positioned immediately above the non-revolute cap-ring G surmounting the rotary knitting-cylinder N . The device is connected to the latch-ring so as to move or swing bodily with it. As thus arranged, the ends of the severed threads extending inward from the

web are comparatively short. The jaws or cutting-blades are maintained in the normally closed position, as indicated in Fig. 5, during the entire production of the stocking, except at the several points where the threads are to be severed. When a thread is moved out of knitting action, by swinging its thread-guide d^1 upward, the lever g is then temporarily tilted by means of its engagement with the relatively positioned or corresponding lug or dog i^1 of the cam-wheel i , thereby opening the jaws, as indicated in Figs. 1 and 4, to receive the thread; the forward movement of the wheel i immediately thereafter operates to disengage the lever from the lug, at which instant the tension of the spring s^2 depresses the free end of the lever onto the concentric rim of the cam-wheel, and through the means operatively connecting the said lever and blade b^1 quickly closing the jaws, thereby severing the thread from the web, its other end portion (which is connected to the supply cop) then being held or confined upon the plate B by the binder a^2 . The binder, it may be stated, becomes operative to thus hold the thread just before the cutting-jaws sever it.

A suitable cam-like projection n formed on the under-side of plate B serves to prevent the web from moving upward on the needles. A spring-like member o may be employed for insuring proper contact of the cutting members b b^1 .

What I claim and desire to secure by U. S. Letters Patent is:

100

1. A knitting machine having in combination a latch-ring, a cutting member mounted thereon, a cam-shaft, and means for operating said cutting member from said cam-shaft.

105

2. A knitting machine having in combination a latch-ring, a cutting member mounted thereon, said cutting member being movable with relation to said latch-ring, a cam-shaft, and means for operating said cutting member from said cam-shaft.

110

3. A knitting machine having in combination a latch-ring, a cutting member mounted thereon, a lever for operating said cutting member, a cam-shaft, and a connection from said cam-shaft to said lever.

115

4. A knitting-machine having in combination a latch-ring, a cutting member mounted thereon, a lever for operating said cutting member also mounted on said latch-ring, a cam-shaft, a member connected to said lever and adapted to be operated by said cam-shaft.

120

5. A knitting machine having in combination a pivoted latch-ring, a cutting member mounted thereon, a lever pivoted on said latch-ring for operating said cutting member, said lever being arc-shaped at one side of its pivot, an operating cam, and a connection from said cam to said lever.

125

6. A knitting machine having in combination a pivoted latch-ring, a cutting member mounted thereon, a lever pivoted on said latch-ring for operating said cutting member, said lever being provided at one side of its pivot with a curved slot described approximately from the pivot of said latch-ring as a center, an operating cam and a connection from said cam to said lever.
- 10 7. In an automatic circular knitting machine, a needle-cylinder, a pivoted latch-ring, a cutting device, said cutting device comprising a jaw member fixed to the latch-ring and a jaw member capable of movement with relation to the latch-ring, an arc-shaped lever pivoted to the latch-ring and connected to said movable jaw member, and a cam-actuated connection jointed to the outer end of the arc-shaped lever.
- 15 8. A knitting machine having in combination a needle-cylinder, a latch-ring adapted for angular movement located above said needle-cylinder, a cutting device having a blade normally located within the needle-20 row of said cylinder, secured to and relatively stationary with the latch-ring, a pivoted shearing blade mounted to coöperate with the said relatively stationary blade-member of the cutting device, a two-arm operating lever pivoted to and angularly movable with the latch-ring, the inner arm of said lever being connected to the said pivoted shearing blade, and intermittently actuated means connected to the outer arm 25 of said pivoted operating lever, whereby the latch-ring is adapted to be oscillated on its pivot without imparting normal cutting movement to the pivoted shearing blade.
- 30 9. In a knitting-machine, provided with a swinging latch-ring, a thread-severing device, secured to and bodily movable with the latch-ring, including in its construction a pair of shearing jaws, means for opening and closing the jaws at predetermined intervals, and having an element of said jaw-35 actuating means mounted on and movable with the latch-ring, constructed and arranged whereby the latch-ring, with its connected members, may be readily swung or 40 oscillated on its pivot through a circular
- arc without changing or altering the angular relation of the jaws to each other.
- 45 10. A knitting machine having in combination a latch-ring, a supporting member secured to said latch-ring, a thread-severing member mounted on said supporting member, an operating lever adapted to actuate said thread-severing member, a cam-shaft, and a connection from said cam-shaft to said operating lever.
- 50 11. A knitting machine having in combination a latch-ring, a supporting member secured to said latch-ring, a thread-severing member mounted on said supporting member, an operating lever mounted on said supporting member, a connection from said operating lever to said thread-severing member, a cam-shaft, and a connection from said cam-shaft to said operating lever.
- 55 12. A knitting machine having in combination a latch-ring, a supporting member secured to said latch-ring, a thread-severing member mounted on said supporting member, an operating lever adapted to operate said thread-severing member, a cam-shaft, and means carried thereby for operating said lever.
- 60 13. A knitting machine having in combination a pivoted latch-ring, an operating member mounted thereon, a lever mounted on said latch-ring for actuating said operating member, said lever being provided with a curved slot described approximately from the pivot of said latch-ring as a center, and an operating connection engaging said slot.
- 65 14. A knitting machine having in combination a pivoted latch-ring, an operating member mounted thereon, a lever mounted on said latch-ring for actuating said operating member, said lever being provided with a curved slot described approximately from the pivot of said latch-ring as a center, an operating cam, and a connection from said cam to said lever.
- 70 In testimony whereof I have affixed my 75 signature in presence of two witnesses.
